HERMAN SCHMIDT, OF NEW YORK, N. Y., ASSIGNOR TO ERNEST B. PRIEBE AND WARREN C. DRAKE, BOTH OF INWOOD, NEW YORK.

TWYER CONSTRUCTION FOR FURNACES AND UNDERFEED STOKERS.

1,380,844.

Specification of Letters Patent. Patented June 7, 1921.

Application filed August 31, 1918. Serial No. 252,230.

To all whom it may concern:

Be it known that I, HERMAN SCHMIDT, a citizen of the United States, residing at New York, in the county of New York and State of New York, have invented certain new and useful Improvements in Twyer Construction for Furnaces and Underfeed Stokers, of which the following is a specification.

10 This invention is a novel twyer construction for automatic stokers, especially underfeed stokers. The general object of the invention is to improve the efficiency, durability and convenience of twyer constructions and of furnaces and stokers embodying the same. Particularly, the invention has to do with the improvement of the construction and arrangement of the twyers, giving a novel and effective mode of air discharge into the fuel bed, with the purpose of promoting the combustion and minimizing the formation of clinkers and the accumulation of refuse upon the grate and at the bridge wall. A further object is to 20 minimize the sifting through the twyers of fine coal, which has been a decided objection, especially in the types of furnace in which the twyers are reciprocated; this objection being eliminated herein by the mode of discharge of air through the air orifices or nozzles. A further object is to maintain clear and free of obstruction the air exits or nozzles of the twyers which in prior constructions have had a tendency to clog, thus 30 impeding the proper flow of air into the fuel bed. Other advantages of the present invention will be made clear in the hereinafter following description of one or more embodiments thereof or will be understood 35 to those skilled in the art.

To the attainment of the above objects and advantages, the present invention consists in the novel features of construction, arrangement, combination and detail hereinafter described or illustrated.

Figure 1 is a vertical longitudinal section on the line 1—1 of Fig. 2 showing portions of a furnace and stoker having incorporated therein the principles of the present invention.

Fig. 2 is a transverse section taken on the line 2—2 of Fig. 1.

Fig. 3 is a section similar to Fig. 1, showing several successive twyer members on an enlarged scale.

Fig. 4 is a side elevation of one of the twyer members of Figs. 1 to 3.

Fig. 5 is a top plan view of one of such twyer members, partly broken away.

Fig. 6 is a transverse section taken on the line 6—6 of Fig. 3.

Fig. 7 in plan view, and

Fig. 8 in section on the line 8—8 of Fig. 7, show a modified form of twyer construction embodying the present invention.

The front wall 10 and bridge wall 11 of an illustrative type of furnace are shown in Fig. 1 and the position of a boiler 12 is there indicated. An underfeed stoker is shown, this for convenience, being indicated of the well known Riley type and the general stoker features, being largely in accordance with the Riley stoker, are not made the subject of claim herein. These features are shown for the purpose of disclosing one mode of practising the present invention and will not be fully herein described since the details are otherwise obtainable, for example from the patent of Riley No. 1,322,822, patented November 25, 1919. It will, of course, be understood that the present invention could be applied on various other types of furnace or stoker.

I partially describe the illustrated stoker as follows. I have indicated the usual exterior coal hopper 13 beneath which is the infeeding ram 14 driven from a crank 15 so as to reciprocate within a casing 16, the ram thereby forcing the coal from the hopper inwardly through the throat or entrance 17 of the furnace. As seen in Fig. 2 there are a series of rams and entrances and within the furnace a corresponding series of retorts 18 into which the entering coal passes, the coal resting on the retort bottom or plate 19. The space beneath the retorts may constitute a wind box 20 for the supply of air of combustion to the twyers and fuel bed. Thin plates 21 are shown, preventing the sifting of coal from the retorts into the wind box.

The retorts 18 are constituted by the spacing apart of a series of air boxes 22. Each of these air boxes comprises side walls 23 and a bottom wall 24 suitably apertured to freely admit air from the wind box. It will be understood that in usual practice the respective air boxes sustain twyers which in turn sustain portions of the fuel bed and admit forced drafts of air thereto. The

construction and arrangement of twyers herein disclosed is a departure from heretofore known constructions.

Fig. 1 shows roughly the line of the fuel bed 25 overlying the retorts and air boxes. The rear or lower portion of the bed rests on a dump plate 26 which is intermittently lowered and raised by means of a roller 27. This roller can be adjusted rearwardly and forwardly by a rack and pinion device 28. The forward end of the dump plate 26 is connected by a link 29 with the rear or lower end 30 of the grate. This part of the grate is slidingly supported on bearing plates 31 so that the grate can be moved rearward and forward as is frequently done in this type of stoker. When the grate moves rearwardly the dump plate descends and the latter rises when the grate returns forwardly.

20 Reciprocated by the connections which operate the ram 14 is shown a bar 32, this serving to convey a reciprocation or agitating movement to a stout cylinder or plunger 33. There will be a plurality of such plungers and they extend inwardly through the furnace front wall and connect with the upper end of the grate. As the result of this construction, the entire grate reciprocates rearwardly and forwardly substantially as indicated by the double arrow 34.

Coming now more particularly to the features of the present invention I have shown, above and resting upon the side walls 32 of each of the air boxes, a series of twyer members 35. The general arrangement is shown in Figs. 1 and 2, Figs. 3 and 6 show the relative arrangement of successive twyer members, while Figs. 4 and 5 are exterior views of a single member.

40 What may be called the body portion 36 of each twyer member is the main transverse portion thereof and this at the opposite side edges is shown as having downward flanges 37. Each of these flanges has small air discharge openings 38 and larger ones 39 for delivering air laterally into the fuel bed within each retort. The downward flange 37 of each twyer member rests directly upon the next lower twyer member, the relative position being determined as will be explained. The entire bank of tuyers is supported directly upon the side walls 23 of the air boxes and for this purpose each twyer side plate or flange 37 is extended forwardly at 40, each extension having an inclined foot or flange 41 of suitable construction and location to rest upon the retort wall 23. As clearly seen in Figs. 1 and 3 the several twyer members snugly nest together and form a solid united construction with substantially no openings except the lateral openings 38 and 39 already referred to, and upward openings to be described.

The transverse or body portion 36 of each

twyer member is substantially horizontal in a transverse direction, but longitudinally it is formed with a particular contour having inclined portions, ridges and depressions or valleys. The extreme lower or rearmost edge or nose 43 of each twyer member operates with the next lower twyer member to form an outwardly or upwardly directed air exit extending transversely across. Directly above each nose portion 43 is a slanting twyer portion 44 substantially parallel with the upper edges of the retort side plates 23. At the top of the incline 44 the contour declines, forming a ridge 45 and a second or downward slant 46, which in turn is succeeded by a depression or valley 47, succeeding which is a second ridge 48 and a final downward extension 49.

The upward air nozzle or orifice 50, before referred to, is formed between the nose portion 43 of one twyer and the first ridge 45 of the next lower twyer, as indicated, the depression or valley 47 and the second ridge 48 being of valuable service in preventing any coal siftings, which may enter the nozzle 50, from passing into the air box. The valley gathers the siftings and the force of the draft eventually carries them upward into the fuel bed.

The relative arrangement and spacing of the successive tuyers may be secured by means of the spacing pins 51 extending downwardly beneath the forward edge of each twyer member and corresponding recesses 52 formed in the valleys 47, into each of which fits the spacing pin of the next twyer member above. The inner extension 49 may be formed with a notch 53 and in this notch is shown engaged the head of a bolt 54. The several bolts 54 pass downwardly through the air boxes and are secured by nuts beneath the bottom walls 24, so that the entire grate and twyer construction is firmly bound in position.

In order to complete the construction of the grate I have shown at the top of the series of tuyers a twyer 55 of special form, co-operating with the twyer beneath and forming a proper terminus for the upper end of the grate. Similarly a special twyer 56 is shown at the bottom of the series, and in some cases there may advantageously be provided intermediate special tuyers 57 between the twyer 56 and the dead plate 58, from which the fuel bed passes on to the dumping grate 26.

The modification shown in Figs. 7 and 8 is applicable to a stoker wherein one half of each twyer system shifts forwardly while the other half shifts rearwardly giving an effective agitating movement. Also this modification shows a twyer with rounded nose. The twyer is shown split longitudinally into two opposite parts 35^a and 35^b,

one of which may be moved forwardly while the other is moved rearwardly. Each half comprises a depression 47^a or 47^b through which air may be discharged upwardly between two successive twyers. Each half member has a downwardly extending spacing pin 51^a or 51^b and a recess 52^a or 52^b for the spacing pin of the next higher twyer. Also each half member has a notch 53^a or 10 53^b for downwardly extending bolts arranged to firmly secure the solidity of the structure. The downwardly extending lugs 60 are adapted to coöperate with preexisting parts of the Riley stoker to properly position the 15 twyer members.

I believe that with the present invention I am the first to provide a twyer construction and operation, as described, the same being shown applied to a furnace grate of 20 the type having one or more inclined air boxes, beside and above which the fuel advances toward the furnace rear. The invention in an important aspect consists in a twyer construction comprising a series of 25 flatwise twyer members resting in overlapping relation upon each other above the air box, each member having a ridge spaced sufficiently from the outer edge of the next higher member to form between them an 30 outwardly and upwardly directed air nozzle. This nozzle, the exit of which is marked 50, Fig. 3, is seen to be a tapering or converging nozzle or passage so that the air passes effectively to the exit and is therefrom 35 forcibly discharged upwardly into the fuel bed. The space between the portions 47, 48 and 49 of one twyer and the portions 44, 45 and 46 of the next higher one is fed freely by air from beneath and this air 40 passes out laterally through openings 38 and 39 into the opposite retorts and longitudinally through the orifice 50, which extends substantially the full width of the twyer, so that air is effectively fed to all parts of 45 the fuel bed. Therefore, the upward air through the nozzle of the present invention supplements the lateral air which passes into the retorts. The lateral orifices 38 and 50 50 are the larger and thus air is fed effectively throughout the fuel within the retorts. The shallowest parts of the fuel bed, that is, above the twyer members, are supplementally fed with air by the successive orifices or 55 nozzles 50. Thus all parts of the fuel bed are effectively and thoroughly reached by the air of combustion and this reduces the tendency of clinkers and improves the operation of the furnace. The arrangement of the 60 successive slanting portions 44 in substantial alinement is found in practice to give an effective fuel support over which the fuel bed passes without hindrance and without tendency to clog the orifices 50. The orifices

substantially do not break the continuity of 65 the supporting surface and yet maintain their effective air supplying operation. The valley or depression 47 beneath each twyer edge or nose 43 receives any fine material 70 that tends to sift through, but this fine material is unable to sift down into the air box because it is effectively held in the depression until again driven outwardly into the fuel bed by the constant blasts of air. The spacing pins or pieces 51 fitting in corresponding recesses maintain the predetermined relation of the parts, and the inwardly extending portions 40 and 41 give proper connection and support of the twyer system upon the inclined air box, the entirety being 75 80 held securely by the downward bolts, which engage the interior portions of each twyer member and are thus protected from deterioration.

It will be noted that the air discharge 85 from the nozzles 50 between successive twyer members is substantially upward, as distinguished from horizontally rearward, although not necessarily vertically upward. This feature of an upward nozzle, especially 90 in connection with the valley or basin immediately within the orifice, is of value, as already explained, in preventing sifting of ashes or coal into the air boxes. This is especially true with furnaces having reciprocating tuyers, and heretofore there has been substantial difficulty with coal siftings dropping into the air passages on each reciprocation of the tuyers. It is found that applicant's arrangement minimizes the entry of 100 siftings, and as long as the air flow is continued or when the tuyers do not reciprocate there will be practically no entrance 105 of siftings. Whatever material enters in any case is temporarily held by the valleys and quickly blown out by the movement of air. Any siftings tending to enter the air box through the lateral openings 38 will 110 also be caught and held in the depression or basin 47 until again blown into the fuel bed.

It will thus be seen that there has been described a twyer construction for furnaces and underfeed stokers, embodying the principles and attaining the advantages of the 115 present improvement. Since many matters of design, arrangement and other detail may be variously modified without departing from the principles involved, it is not intended to limit the invention to such materials except in so far as specified in the appended claims.

What is claimed is:

1. For a furnace grate of the type having inclined air boxes between and above which 125 the fuel bed advances descendingly toward the furnace rear, a twyer system overlying each air box, and comprising a series of flat-

- wise members resting in overlapping relation upon each other and relatively arranged to afford a series of air nozzles directed upwardly into the fuel bed overlying said members.
2. For a furnace grate of the type having inclined air boxes between and above which the fuel bed advances descendingly toward the furnace rear, a twyer system overlying each air box, and comprising a series of flatwise members, the rear lower edge of each member so related to the upper edge of the member beneath as to form between them an upwardly directed transverse air nozzle.
3. For a furnace grate of the type having inclined air boxes between and above which the fuel bed advances descendingly toward the furnace rear, a twyer system overlying each air box, and comprising a series of flatwise members resting in overlapping relation upon each other, their outer surfaces in alinement, affording a substantially continuous inclined supporting surface for the fuel, and successive members relatively arranged to afford a series of air nozzles directed upwardly between the members into the fuel bed overlying said members.
4. For a furnace grate of the type having inclined air boxes between and above which the fuel bed advances descendingly toward the furnace rear, a twyer system overlying each air box, and comprising a series of flatwise members resting in overlapping relation upon each other and relatively arranged to afford between each two adjacent members an air nozzle directed upwardly into the fuel bed, and a valley formed beneath each nozzle adapted to catch siftings and from which the same may be blown upwardly into the fuel bed.
5. For a furnace grate of the type having inclined air boxes between and above which the fuel bed advances descendingly toward the furnace rear, a twyer system overlying each air box, and comprising a series of flatwise members, the rear lower edge of each member spaced from the next member beneath, and the latter formed with a ridge and valley beneath such edge, so shaped that a converging upwardly directed nozzle is formed.
6. For a furnace grate of the type having inclined air boxes between and above which the fuel bed advances descendingly toward the furnace rear, a twyer system overlying each air box, and comprising a series of flatwise members, the rear lower edge of each member so related to the upper edge of the member beneath as to form between them an upwardly directed transverse air nozzle, and the lateral sides of each member having apertures for discharging air into the fuel bed at the sides of the air box.
7. For a furnace grate of the type having one or more inclined air boxes beside and above which the fuel bed advances toward the furnace rear, a twyer construction comprising a series of longitudinal twyer members arranged in overlapping relation upon each other, each member having a valley or depression spaced sufficiently below the extreme edge of the next higher member to form between them an upwardly directed air nozzle.
8. Twyer construction as in claim 7 and wherein a spacing piece maintains the relations of the nozzle forming portions of each two adjacent members.
9. Twyer construction as in claim 7 and wherein each twyer member has side walls extending inwardly beyond the body of the member to where the beveled inner ends of the walls engage the inclined air box.
10. Twyer construction as in claim 7 and wherein each twyer member has side walls extending inwardly beyond the body of the member to the air box, and a downwardly extending bolt from the concealed or inner end of the body serves to secure the member in place.
11. Twyer construction as in claim 1, and wherein the adjacent parts of each pair of twyer members are so formed that the upward air nozzle between them is of converging character.
- In testimony whereof, I affix my signature hereto.

HERMAN SCHMIDT.
